UNITED STATES PATENT OFFICE

HENRY G. HUNT, OF GRANVILLE, MASSACHUSETTS

DRUM

Application filed February 23, 1928. Serial No. 256,275.

This invention relates to drums and has for its object the accomplishment of improved tonal qualities for a drum. A further object of the invention is to provide a drum structure having greater utility and serviceability than drums now in use.

In accordance with the invention, two complete drum units are arranged in superposed spaced relation to provide an air chamber between the inner facing heads of the two drum units. I have discovered that such an arrangement, with the provision of an air chamber of appropriate dimensions and sufficiently open around its periphery 15 at the sides of the drum, will give a very pleasing tone quality which is quite distinct from that given by the ordinary drum.

While this feature of improved tone quality is particularly aimed at in the present invention, a further consequence of the arrangement mentioned is that additional utility may be given to the drum structure by the location of the snare heads or head on the inside of the drum structure, thus 25 presenting both of the opposite outside heads for use as beater heads. In other words, the drum structure of the present invention may have the sound qualities of a snare drum, and yet be beaten on either side. This characteristic becomes useful 30 in such emergencies as when one of the beater heads is ruptured during playing, for in that event the drum need only be turned over and the playing continued. The 35 drum may be played with a snare on either one or on both of the inside heads of the drum structure and different tone qualities can be produced by changes in the use of the snare. For example, with a snare in 40 use on only one of the drum units, the combined tone effect of a tom-tom and snare drum is attained, and this tone effect is still further varied depending upon whether the 45 beating of the drum is upon the snare drum unit or the tom-tom unit.

The novel features and advantages of the invention will be observed from the following description thereof which, for purposes 50 of disclosure, is illustrated in the form at

present preferred by means of the accompanying drawings, in which:—

Fig. 1 is a partial plan view of a drum embodying the novel features of the invention;

Fig. 2 is a side elevational view of the drum shown in Fig. 1;

Fig. 3 is an enlarged sectional elevational view taken on the line 3—3 of Fig. 1;

Fig. 3^a is a partial elevational view of a drum showing a modification of the clamping and tensioning means for the drum; and

Fig. 4 is a similar sectional view taken on the line 4—4 of Fig. 2.

Referring to the drawings in detail, the drum structure comprises two complete drum units indicated generally at 1 and 2 and arranged in superposed spaced relation so as to provide a central air chamber between the inner heads of the units. The means for spacing the drum units apart are preferably designed to leave this central air chamber open substantially throughout its entire periphery at the sides of the drum.

Each drum unit 1 and 2 of the complete structure includes a cylindrical shell 3 and 3' respectively, which are provided with the usual vent holes 4. Upon the cylindrical shell 3 is mounted the outer head B and the inner head S, and upon the cylindrical shell 3' is mounted the outer head B' and inner head S'. In my preferred arrangement, as shown, the outer heads B and B' of the drum structure are to be used as beater heads and one or both of the inner heads S and S' are to be used as snare heads. It is to be understood, however, that the heads of the separate drums may be employed in a relation other than as specified and that any one of the heads may be used as a snare head, and either one or both of the outer heads as a beater head.

Outer hoops 8 and 8' are provided for fitting over the outer heads B and B' so as to abut rings 6 and 6' thereof, while similar inner hoops 9 and 9' fit over the inner heads and are adapted to abut against rings 7 and 7' thereof.

The drums 1 and 2 are preferably held in

spaced apart relation by some convenient means such as spacers 10 which are disposed at spaced intervals around the rims of the drums so as to engage the inner hoops 9 and 9'. These spacers may take any form desired, such as hollow thimbles or the like, and may be held in place by dowels 11 or screw threaded member which pass therethrough and have their opposite ends disposed in suitable recesses or engaged with threaded holes, in the edges of the rings.

Clamps for clamping the parts of each drum together and to tension the heads thereof as well as for clamping the parts, 15 constituting the separate drums, together consist of hooks 14 and 14' for engaging the outer edges of the hoops 8 and 8' which have angularly disposed plate portions 15 and 15'. These plates are provided with 20 suitable apertures for receiving wing couplings screws 16, which are provided with collars 17 for abutting the plates of the clamps and threads for engaging nuts 19 disposed at a side of a plate of the other 25 clamp of a pair, all as shown. Wings 20 on the ends of the screws facilitate their being rotated by hand so that as the screws are screwed into the nuts, the clamps of a pair are urged or drawn towards one another.

The inner hoops 9 and 9' are, as described, held or fixed in spaced relation by the spacers 10 so that as the clamps are tightened or moved towards one another, the 35 outer hoops 8 and 8' are moved inwardly of their shells towards the inner hoops 9 and 9'.

As the hoops 8 and 8' are moved towards one another they act against the outer head 40 rings 6 and 6', and stretch or tension the heads B and B' and at the same time tend to move the shells 3 and 3', which in turn act upon the heads S and S', the edges of which are held by the rings 7 and 7' abutting the hoops 9 and 9'. By thus moving the 45 outer hoops and rings towards one another or towards the inner hoops and rings, the heads may be stretched or tensioned to the degree desired and the parts in effect 50 clamped to inner hoops 9 and 9'.

The tension of the heads may of course be varied at will, depending upon the condition of the heads, their characteristics, etc.

It may well be desired to provide means 55 for clamping the parts of one drum together and for tensioning the heads independently of the other and to provide in addition thereto, independent means for clamping the separate drums together so that their adjacent inner heads, which I prefer to term snare heads, may be held in a spaced relation to form the air chamber referred to.

This may be accomplished by means of the modified form of clamping means shown in 65 Fig. 3. In this case pairs of hooks 25 and

26 engage the outer and inner hoops 8 and 8' and 9 and 9' of each drum and receive tensioning screws 27. These screws 27 as in the former case, are provided with wings 28 and collars 29 and have their ends in screw threaded engagement with nuts 30.

These clamping devices are spaced around the drums as may be desired, so that by tightening them, the rings, shells, and associated parts of each drum may be moved 75 independently of those of the other so as to tighten or tension the heads thereof, thus rendering it possible to tension the heads of one drum independently of the other, as will be desirable when the heads are unlike 80 or require various degrees of tensioning to obtain the tone desired.

Intermediate the clamps described, other clamps for clamping or holding the drum together are provided. These may comprise 85 hooks 30' and 31 which engage the outer hoops 8 and 8' and rods 37, screw threaded by right and left hand threads on its opposite ends in suitable nuts 33, which bear against the clamps so that by turning these 90 screws 37 the drums may be secured together. The parts comprising the clamps will preferably be so arranged that the clamps previously described or their action will not be interfered with, as these latter 95 clamps are tightened for holding the drums in their superposed relation. As many of these clamps may be employed as may be desired around the periphery of the drums, but since they are not intended for tensioning the heads, they of course need not be as numerous as the previously described clamps.

Snares N and N' are provided which may be of ordinary form and preferably extend across the adjacent faces of the snare heads 100 S and S'. The snares of one head may be in parallel relation with those of the other, or they may be disposed in an angular relation with respect thereto, all as desired.

Any number of snares may be employed 110 and will depend to a large extent upon the tone effect it is desired to obtain and, as is usual, these may pass back and forth through suitable openings in the shells and engage with snare tensioning or adjusting 115 devices 15 of usual form, disposed on the outer side of the shells.

It will be noted that in addition to the outer head B and inner head S, constituting 120 a pair of heads of one drum, as is usual, there is provided an inner head S' spaced from the head S to provide an air space therebetween and, as well that another outer head B' is spaced from the head S'.

Thus, a plurality of heads spaced apart to 125 provide air spaces therebetween are provided, not only to improve the tonal qualities of the drum, but are arranged so as to provide as well a pair of separate or independent drum structures which are clamped 130

together to form a strong, rigid drum structure.

Snares may be located adjacent any of the heads as well as on either side of any of the heads or adjacent as many as may be desired, but according to the preferred form of the invention it is desirable to locate sets of snares adjacent the two inner heads. With this arrangement, either of the outer beater heads has a snare head therebelow, and according to the novel construction, there is another head or heads below and spaced from the snare head which functions to cooperate therewith to produce the tone effect desired.

Various changes may be made in the form of the invention without departing from the spirit and scope thereof, and I prefer therefore to be limited, if at all, by the appended claims rather than by the foregoing description.

What I claim is:

1. A drum structure comprising in combination, a pair of drums in superposed relation, each drum including an outer head and an inner head, the inner head of one drum being spaced from the inner head of the other drum to provide a central air chamber between the two drums, and means at the peripheries of said drums to secure them in the relation specified.

2. A drum structure comprising in combination, a pair of drums in superposed relation, each drum including an outer head and an inner head, the inner head of one drum being spaced from the inner head of the other drum to provide a central air chamber between the two drums, and means at the peripheries of said drums to secure them in the relation specified, said air chamber being open substantially throughout its periphery at the sides of said drum structure.

3. A drum structure comprising in combination, a pair of drums in superposed relation, each drum including an outer head and an inner head, the inner head of one drum being spaced from the inner head of the other drum to provide a central air chamber between the two drums, means at the peripheries of said drums to secure them in the relation specified, and a snare mounted across the face of one of the inner heads.

4. A drum structure comprising in combination, a pair of drums in superposed relation, each drum including an outer head and an inner head, the inner head of one drum being spaced from the inner head of the other drum to provide a central air chamber between the two drums, means at the peripheries of said drums to secure them in the relation specified, and a snare mounted across the face of each of said inner heads.

5. A drum structure comprising in combination, a pair of drums in superposed rela-

tion, each drum including an outer head and an inner head, the inner head of one drum being spaced from the inner head of the other drum to provide a central air chamber between the two drums, and means for clamping said drums together said means also serving to tension the several heads of said drums.

6. A drum structure comprising in combination, a pair of drums in superposed relation with the inner head of one drum spaced from the inner head of the other drum to provide a central air chamber between the two drums, means for tensioning the heads of each drum independently of those of the other drum, and means for clamping the drums together so as to hold the adjacent inner heads in spaced relation.

7. A drum structure comprising in combination, a pair of drums in superposed relation, each drum including an outer and inner head, spacing members interposed between the rims of said inner heads to provide a central air chamber between said drums, and clamping members engaging the rims of said outer heads for securing the drums together.

In testimony whereof I have affixed my signature.
